US0D1032517S

(12) **United States Design Patent** (10) Patent No.: **US D1,032,517 S**
(45) Date of Patent: ** Jun. 25, 2024

(54) **SEMICONDUCTOR MODULE**

(71) Applicant: **ROHM CO., LTD.**, Kyoto (JP)

(72) Inventor: **Hideo Hara**, Kyoto (JP)

(73) Assignee: **ROHM CO., LTD.**, Kyoto (JP)

(**) Term: **15 Years**

(21) Appl. No.: **29/823,888**

(22) Filed: **Jan. 20, 2022**

(30) **Foreign Application Priority Data**

Jul. 29, 2021 (JP) ..... 2021-016449 D

(51) **LOC (14) Cl.** **13-03**

(52) **U.S. Cl.**

USPC **D13/182**

(57) **CLAIM**

The ornamental design for a semiconductor module, as shown and described.

DESCRIPTION

FIG. 1 is a front, top and right side perspective view of a semiconductor module showing my design; FIG. 2 is a rear, bottom and left side perspective view thereof;

FIG. 3 is a front view thereof;

FIG. 4 is a rear view thereof;

FIG. 5 is a top plan view thereof;

FIG. 6 is a bottom plan view thereof; and,

FIG. 7 is a right side view thereof, the left side view being an identical image of FIG. 7.
